TO JOSEPH S. DAVIS, OF LOS ANGELES, CALIFORNIA

AUTOMATIC FUEL CONTROL DEVICE FOR INTERNAL COMBUSTION ENGINES

Application filed January 21, 1931. Serial No. 510,142.

This invention relates to a gaseous or vaporized fuel control device adapted to be connected to the intake manifold or incorporated with the carburetor of an internal combustion engine, more particularly to the engines of motor vehicles.

Should the accelerator throttle valve be suddenly closed while the engine is rotating faster than the so-called idling speed, several undesirable and detrimental conditions take place, viz., a loss of fuel, a discharge of unburnt obnoxious gases, and in some instances a dilution of the lubricating oil.

After the accelerator throttle is closed under the above conditions a degree of vacuum is created in the intake manifold due to reducing or checking the supply of gaseous mixture from the carburetor to the engine cylinders.

Should the above stated condition exist for any length of time, i. e., while the vehicle is coasting down grade or between traffic intersections with the gears in mesh and the clutch engaged, or between gear shifts when the engine is speeded up and the accelerator throttle suddenly closed, the intake manifold, cylinders and exhaust manifold become filled with unburnt gaseous fuel due to insufficient compression, and lack of time for proper combustion.

The accumulation of unburnt fuel thus formed is suddenly expelled through the exhaust during the coasting period and when the throttle is again opened or upon a return to idling of the engine. This discharge of unburnt fuel into the atmosphere is not only very obnoxious to occupants of the vehicle and others within its range, but results in a loss of fuel which although imperceptible during each of the above stated intervals amounts to considerable when taken collectively, also the unburnt fuel works past the pistons into the crank case resulting in a dilution of the lubricating oil therein causing increased engine wear.

The object of this invention is to provide a device of the character referred to which will automatically cut off the fuel supply to an internal combustion engine should the accelerator throttle valve be closed while the engine

is rotating faster than the so-called idling speed and thereby prevent any vaporized fuel from the carburetor entering the engine until the accelerator throttle valve is again opened or upon a return to idling speed.

It is also understood that during the operation of an internal combustion engine when the accelerator throttle valve is opened, after the engine has been running at idling speed, or upon a return to idling speed after the engine has been running faster than idling speed with the accelerator throttle valve closed, the degree of vacuum is at the lowest point.

It is, therefore, another object of the present invention to provide means whereby a charge of fuel may be introduced into the intake manifold of an internal combustion engine independently of the suction and operable only when the suction is reduced below normal operating conditions in order that the engine will not stall for lack of fuel.

Other objects and advantages will be apparent from the following description, reference being had to the accompanying drawings, in which—

Fig. 1 is a side elevation of an internal combustion engine showing the automatic fuel control device connected to the intake manifold.

Fig. 2 is a longitudinal section taken through the fuel control device.

Fig. 3 is a fragmentary detail section taken on line 3—3 of Fig. 2.

Referring more specifically to the drawings, 10 designates a conventional internal combustion engine, including a carburetor 11, intake manifold 12, and exhaust manifold 13. The improved gaseous fuel control device generally designated at 14 is adapted to be connected to the intake manifold as shown in Fig. 1, or it may be formed integral with or incorporated with the carburetor above the accelerator throttle valve.

Control device 14 not only automatically cuts off the fuel supply from the carburetor to the engine under the conditions above referred to, but is provided with what may be termed an auxiliary carburetor which serves to supply fuel to the engine during idling

speed, hence the accelerator throttle valve designated at 16 should be adjusted, also the usual idling ports therein closed or plugged so that it will entirely cut off the fuel from the carburetor when it is closed. The needle valve of the main carburetor should also be adjusted to compensate for the fuel admitted through the auxiliary carburetor of the device when the accelerator throttle is opened.

10 Referring more specifically to Fig. 2, 18 designates a body member or casting having an internally threaded boss 19 formed on its bottom face into which is screw threaded a usual coupling or union 20 including a nipple 21 adapted to be screw threaded into an opening formed in the intake manifold.

15 Liquid fuel is fed into the device from the usual reservoir or vacuum tank (not shown) through a pipe line 22 which is connected by 20 a union to an inlet fitting 23 preferably provided with a filtering screen 24, the fluid passing through the screen thence through ports 25 formed in a member 26 having a bore 27 normally closed by a float valve 28 when 25 the engine is not running.

20 Float valve 28 is connected by a rocker arm 29 to a float 30 disposed in a chamber 31 formed in the body member 18, fluid F in the float chamber passes through a port 32 controlled by a needle valve 33 into a reservoir 34 through a port 35, the fluid seeking a level 30 in the float chamber and reservoir.

25 Mounted in the upper end of the reservoir is a primary air admission tube 36 or regulator which registers with a port 37 communicating with a vaporizer or mixing tube generally designated at 38. The mixing tube or vaporizer 38 consists of a tubular member 39 screw threaded into the upper end of a 40 recess 40, and is provided with a tapered bore 41 in which is concentrically disposed an adjustable air admission tube 42 having an externally tapered face.

45 The above described parts operate in exactly the same manner as a usual carburetor, and serve to admit fuel to the engine during idling speed, it being necessary that the accelerator valve be closed in order that the device will perform its intended functions in 50 a manner more fully hereinafter described. It being particularly noted that due to independent adjustment and relatively small diameter of the mixing or vaporizing tube the idling mixture may be very accurately controlled, resulting in smoother running of the 55 engine at idling speed than is possible to attain with the usual or main carburetor. The mixture from the idling jet or vaporizer passes through a port 43 into an annular recess 44 formed in the body member, ports 45 into a bore 46 formed in the center member 47 of a diaphragm 48 thence into the intake manifold through the coupling member 20.

60 Diaphragm 48 is mounted in an annular 65 chamber 49 formed in the body member with

its bottom face engaging a washer 50, and is held in place by a nut 51 screw threaded on the portion 52 of the center member projecting through an opening below the recess 44.

65 Slidably mounted in the center member and 70 adjustably secured to the head 53 of the diaphragm is a stem 54 having a tapered valve 55 formed on its lower end which is adapted to engage a seat 56 formed in its lower end when the diaphragm is distended.

75 Mounted in a recess 60 formed in the body member is a valve member 61 consisting of a tubular housing 62 having a tapered seat 63 formed in its lower end, and slidably mounted in said housing is a valve 64 normally urged into engagement with the seat by an expansion coil spring 65. The tension of said spring being regulated by an adjusting screw 66 threaded in sleeve 66a which in turn is 80 threaded into the upper end of the housing.

85 The tubular housing 62 extends through an opening 67 of larger diameter formed in a cover or closure plate 68 removably secured to the body member, the housing having a shoulder 69 engaging a ring or gasket 70 90 closing the upper end of the opening 67.

95 Screw threaded into a recess 71 formed in the body member is a second valve member generally designated at 72 consisting of a housing 73 in which is slidably mounted a valve 74 having a tapered end 75 adapted to engage a seat 76 formed in the lower end of the housing. The valve 74 is normally held out of engagement with the seat by a coil spring 77 connected thereto and to a stem 78 upon which is threaded a nut 79 engaging the upper end of a fitting 80 screw threaded into the housing, the stem being held against rotation by tongues 81 thereon disposed in grooves 81a formed in the fitting. It being 105 understood that the valves 64 and 74 should be adjusted according to the piston displacement of the engine to which each device is applied so that they will operate properly.

110 Suction created in the intake manifold communicates with a chamber 82 (formed in the body member) through a port 83, and mounted in the chamber is a diaphragm 84 which serves to introduce a charge of fluid 115 into the intake manifold to aid in starting or prevent stalling of the engine upon opening of the accelerator throttle valve after it has been closed when the engine is rotating faster than idling speed.

120 Operation: Assuming the accelerator throttle valve is opened a circulation of air passes through ports 85 formed in the fitting 80 of the valve member 72, ports 86 in the valve 74 into the recess 71 (the valve 74 being held open by the spring 77) thence through a port 87 into the chamber 49. The circulation continues through the chamber 49, port 88, valve seat 63, ports 89 formed in the valve 64 (said valve then being unseated against the action of the spring 65), ports 90 125 130

formed in the housing 62 of the valve member 61 into the opening 67 formed in the cover 68, into the chamber 83 through ports 91 formed in the cover 68, thence through the chamber 82 and port 83 into the intake manifold.

During the time the accelerator throttle is opened a limited amount of vaporized fuel also enters the intake manifold.

Upon closing of the accelerator throttle the carburetor of the device functions to furnish fuel during the so-called idling speed. On the other hand should the accelerator throttle be suddenly closed while the engine is rotating faster than idling speed the vacuum created in the intake manifold will tend to exhaust or withdraw air normally circulating through the valve members, chambers and ports above described, whereupon the valve 64 is fully unseated and the valve 74 seated resulting in creating a vacuum in the chamber 49, which in turn causes the valve 55 to seat due to distention of the diaphragm 48, thus simultaneously cutting off the idling fuel supply and any further circulation of air through the valve members 61 and 72. It being understood that atmospheric pressure exerted on the interior of the diaphragm through a port 92 (see Fig. 3) actually effects closing of the valve 55.

When the accelerator throttle is again opened or upon a return to idling speed the valve 74 is instantly unseated (due to decreased suction) whereupon the valve 55 is opened by collapsing or returning to normal position of the diaphragm 48, thus restoring the idling mixture.

The device functions as above described except that during gear shifting the valve 48 automatically opens a moment before idling speed with the accelerator valve still closed during coasting with gears in mesh and each time the clutch is disengaged, thus preventing stalling of the engine during such periods.

From the foregoing it will be seen that as long as the engine is rotating faster than idling speed with the accelerator throttle closed all air or vaporized fuel is entirely cut off from the engine. However, under certain conditions due to sudden reduction in suction when the accelerator throttle is opened the engine has a tendency to stall for lack of fuel. This is prevented by the diaphragm 84 which functions as follows:

During the interval after the accelerator throttle is closed as above described the diaphragm 84 will be distended as indicated by dotted lines (see Fig. 2) upon opening of the accelerator throttle the vacuum will be immediately reduced whereupon said diaphragm will return to normal position resulting in discharging a quantity of liquid fuel drawn into its interior during distension through a port 94 communicating with

the reservoir 34, back through the port into the intake manifold, this charge of fuel serving to aid in starting of the engine.

From the foregoing it will be seen that the device effectively prevents any fuel entering the engine except when it is required to produce power and during the so-called idling speed thereby preventing an accumulation of unburnt fuel in the engine cylinders, intake and exhaust manifold.

I claim:

1. The combination with an internal combustion engine including a carburetor, an accelerator throttle valve and an intake manifold of a device comprising a body member adapted to be connected to the intake manifold of the engine, a gaseous fuel vaporizer carried by said body member adapted to supply fuel to the engine during idling speed, a diaphragm mounted in a chamber formed in said body member, a valve actuated by said diaphragm adapted to cut off the fuel from said vaporizer upon closing of the accelerator valve when the engine is rotating faster than idling speed, a valve member carried by said body member having a valve normally seated and in communication with the suction created by the engine and the chamber in which said diaphragm is mounted, and a second valve member carried by said body member having a valve normally unseated and in communication with the atmosphere and the chamber in which the diaphragm is mounted, whereby upon closing of the accelerator valve the valve of said diaphragm will be seated thereby cutting off the gaseous fuel supply and circulation of air through the device into the engine.

2. The combination with an internal combustion engine including a carburetor, an accelerator throttle valve and an intake manifold of a device comprising a body member adapted to be connected to the intake manifold of the engine, a gaseous fuel vaporizer carried by said body member adapted to supply fuel to the engine during idling speed, a diaphragm mounted in a chamber formed in said body member, said diaphragm including a center member extending into a recess below the bottom face of the diaphragm and through an opening formed in the body member, a valve connected to the head of said diaphragm and slidably mounted in the center member, there being a port formed in the body member communicating with the recess below the diaphragm and the fuel vaporizer, and ports in the center member above the diaphragm valve, a valve member carried by said body member having a valve normally seated and in communication with the suction created by the engine and the chamber in which said diaphragm is mounted, and a second valve member carried by said body member having a valve normally unseated and in communication with the atmosphere.

3. The combination with an internal combustion engine including a carburetor, an accelerator throttle valve and an intake manifold of a device comprising a body member adapted to be connected to the intake manifold of the engine, a gaseous fuel vaporizer carried by said body member adapted to supply fuel to the engine during idling speed, a diaphragm mounted in a chamber formed in said body member, said diaphragm including a center member extending into a recess below the bottom face of the diaphragm and through an opening formed in the body member, a valve connected to the head of said diaphragm and slidably mounted in the center member, there being a port formed in the body member communicating with the recess below the diaphragm and the fuel vaporizer, and ports in the center member above the diaphragm valve, a valve member carried by said body member having a valve normally seated and in communication with the suction created by the engine and the chamber in which said diaphragm is mounted, and a second valve member carried by said body member having a valve normally unseated and in communication with the atmosphere.

- and the chamber in which the diaphragm is mounted, whereby upon closing of the accelerator throttle valve when the engine is rotating faster than idling speed said first valve 5 will be unseated and the second valve seated whereupon said diaphragm will be distended by atmospheric pressure causing the valve connected thereto to seat thereby cutting off the gaseous fuel supply from the vaporizer 10 and circulation of air through the device into the engine.
3. The combination with an internal combustion engine including a carburetor, an accelerator throttle valve and an intake manifold of a device comprising a body member adapted to be connected to the intake manifold of the engine, a gaseous fuel vaporizer carried by said body member adapted to supply fuel to the engine during idling speed 15 20 25 30 35 40 45 50 55 60 65 70 75 80 85 90 95 100 105 110 115 120 125 130
- 20 a diaphragm mounted in a chamber formed in said body member, a valve actuated by said diaphragm adapted to cut off the fuel from said vaporizer upon closing of the accelerator throttle valve when the engine is rotating faster than idling speed, a valve housing mounted in a recess formed in said body member, a valve slidably mounted in said housing and in communication with the suction created by the engine and the chamber 25 in which said diaphragm is mounted, and a second valve housing mounted in a recess formed in said body member, a valve slidably mounted in said housing normally unseated and in communication with the atmosphere 30 and the chamber in which the diaphragm is mounted, whereby upon closing of the accelerator throttle valve when the engine is rotating faster than idling speed said first valve will be unseated and the second valve seated 35 whereupon said diaphragm will be distended by atmospheric pressure causing the valve connected thereto to seat thereby cutting off the gaseous fuel supply from the vaporizer and circulation of air through the device into 40 the engine.
4. The combination with an internal combustion engine including a carburetor, an accelerator throttle valve and an intake manifold of a device comprising a body member 45 adapted to be connected to the intake manifold of the engine, a gaseous fuel vaporizer carried by said body member adapted to supply fuel to the engine during idling speed, a diaphragm mounted in a chamber formed 50 in said body member, said diaphragm including a center member extending into a recess below the bottom face of the diaphragm and through an opening formed in the body member, a valve connected to the 55 head of said diaphragm and slidably mounted in the center member, there being a port formed in the body member communicating with the recess below the diaphragm and the fuel vaporizer, and ports in the center member 60 above the diaphragm valve, a second dia-
